(57) **CLAIM**

The ornamental design for a quilted rolling storage bag, as shown and described.

DESCRIPTION

FIG. 1 is a perspective view of a quilted rolling storage bag; FIG. 2 is right side view of the quilted rolling storage bag; FIG. 3 is a left side view of the quilted rolling storage bag; FIG. 4 is a top view of the quilted rolling storage bag; FIG. 5 is a bottom view of quilted rolling storage bag; FIG. 6 is a front view of the quilted rolling storage bag; and, FIG. 7 is a rear view of the quilted rolling storage bag. The broken lines of FIGS. 1-7 illustrate stitching which forms a part of the claimed design. The long dash broken lines shown in FIGS. 1, 5, and 7 represent hardware on the wheels and are no part of the claimed design.

1 Claim, 7 Drawing Sheets
